(57) **CLAIM**

The ornamental design for a shelving unit, as shown and described.

DESCRIPTION

FIG. 1 is a perspective view of the shelving unit according to the present invention;

FIG. 2 is a top elevational view thereof;

FIG. 3 is a bottom elevational view thereof;

FIG. 4 is a front elevational view thereof (a rear elevational view is not provided as it is a mirror image of this view);
FIG. 5 is a left side elevational view thereof (a right side elevational view is not provided as it is a mirror image of this view);

FIG. 6 is a perspective view thereof;

FIG. 7 is an exploded perspective view thereof;

FIG. 8 is a perspective view thereof;

FIG. 9 is an exploded perspective view thereof;

FIG. 10 is a front elevational view showing three components of the shelving unit according to the present invention; and,

FIG. 11 is a rear elevational view showing three components of the shelving unit according to the present invention. The broken-lines shading in the Figures is for illustrative purpose only and forms no part of the claimed design.
